CLAIM

The ornamental design for a teeth model, as shown and described.

DESCRIPTION

FIG. 1 is a front elevational view of the teeth model showing our new design;

FIG. 2 is a side elevational view thereof, the opposite side elevational view being a mirror image;

FIG. 3 is a rear elevational view thereof;

FIG. 4 is a top plan view thereof; and

FIG. 5 is a bottom plan view thereof.
